PLAYGROUND CLIMBER OR THE LIKE

John F. Price, Delafield, and Larry L. Johnson, Milwaukee, Wis., assignors to Everwear Park & Playground Equipment, Inc., Oconomowoc, Wis.

Filed Mar. 3, 1971, Ser. No. 120,798

Term of patent 14 years

Int. Cl. D21—03

U.S. Cl. D34—5

FIG. 1 is a front elevational view of a playground climber of the like embodying our new design, the back side being a reverse image of the front side shown;

FIG. 2 is an elevational view taken from one side thereof, the opposite side being a reverse image of the side shown;

FIG. 3 is a top plan view thereof, the bottom being a reverse image of the top shown; and

FIG. 4 is a view in vertical section taken along the plane represented by the line 4—4 in FIG. 2.

We claim:

The ornamental design of a playground climber or the like, as shown and described.
